UNITED STATES PATENT OFFICE

JOSEPH E. WAINWRIGHT, OF BROOKLYN, NEW YORK

VALVE SPRING COMPRESSOR AND REPLACER

Application filed February 16, 1929. Serial No. 340,437.

This invention relates to valve tools of the type employed for compressing and lifting valve springs of internal combustion engines incident to making repairs thereto.

One of the primary objects of my present invention is to provide a simple and rugged valve spring tool which will effectively and positively accomplish the desired result and with the expenditure of a minimum amount 10 of time and effort.

Another salient object of my invention is the provision of a turret head carrying the compressing rack bar and operating crank therefor, the head being rotatable on the 15 frame of the tool, whereby the crank can be disposed in a convenient position for operation and out of the way of parts of the engine and whereby the crank can be placed on one side of the frame or the other for the convenience of left or right hand workmen.

A further object of the invention is the provision of a novel friction lock carried directly by the pinion shaft, for positively locking the pinion and consequently the rack 25 bar in an adjusted position, the lock being of such a character as to permit a fine adjustment to be had.

A further object of the invention is the provision of a novel spring pressed centering 30 pin carried by the rack for engaging the recess in the valve head to permit alinement of the tool with the longitudinal axis of the valve, when the tool is used on the valve for compressing the spring and for centering and holding the spring when the spring is being 35 recompressed for association with the valve stem. The foot of the frame receives a novel dome of conical shape for properly holding the lower end of the spring during the compression thereof.

A still further object of the invention is to provide an improved tool of the above character, which will be durable and efficient in use, one that will be easy to manufacture, and 40 one which can be placed upon the market at a reasonable cost.

With these and other objects in view, the invention consists in the novel construction, arrangement and formation of parts, as will 50 be hereinafter more specifically described,

claimed, and illustrated in the accompanying drawings, in which drawings:

Figure 1 is a perspective view of my improved tool;

Figure 2 is a side elevation of the same 55 showing the tool in use on an engine for compressing a valve spring thereon to facilitate the removal of the holding pin on the valve stem;

Figure 3 is a detail vertical section showing 60 the tool in use for recompressing a spring illustrating the dome associated with the foot of the frame for centering the spring and for receiving the lower hooked ends of the spring holding clip;

Figure 4 is a detail vertical section taken 65 on the line 4-4 of Figure 3 looking in the direction of the arrows;

Figure 5 is an enlarged fragmentary side elevation of the upper end of the frame showing 70 the novel turret head and rack bar, parts being shown broken away and in section;

Figure 6 is a fragmentary top plan view 75 of the improved device;

Figure 7 is a detail vertical section taken 80 on the line 7-7 of Figure 5 looking in the direction of the arrows;

Figure 8 is a side elevation of the jam nut showing the inner face thereof;

Figure 9 is a detail side elevation of the 85 pinion showing the countersunk face thereof;

Figure 10 is a detail side elevation of the operating shaft with the operating crank attached thereto, part of the shaft being shown in section with the crank, the view illustrating the novel construction of the shaft for receiving the pinion and the jam nut, the jam nut and pinion being shown in dotted lines;

Figure 11 is a fragmentary side elevation 90 of one end of the operating shaft illustrating a slightly modified means for holding the jam nut in position, the washer for said means being shown in section;

Figure 12 is a detail vertical section 95 through the lower end of the rack bar and head taken on the line 12-12 of Figure 5 looking in the direction of the arrows;

Figure 13 is a fragmentary side elevation 100 of the tool showing a slightly modified form

of turret head with modified means for locking the head in an adjusted position on the frame;

Figure 14 is a fragmentary plan view showing the foot carried by the lower end of the frame, parts of the foot being shown broken away and in section and illustrating the means which can be employed for adjusting the resilient arms of the foot toward and 10 away from one another;

Figure 15 is a detail horizontal section taken on the line 15—15 of Figure 14 looking in the direction of the arrows illustrating the means for anchoring the adjusting bolt 15 for the resilient arms of the foot in position.

Referring to the drawings in detail, where in similar reference characters designate corresponding parts throughout the several views, the letter A generally indicates my improved tool which comprises a frame 15 of substantially C shape. This frame is preferably formed from a single piece of steel and includes the upper and lower legs 16 and 17 and a connecting vertically disposed body portion 18.

The upper leg 16 supports my novel turret head 19 which forms one of the salient features of my invention. This turret head forms a casing for the operating parts of my tool and this head slidably receives the rack bar 20, which extends vertically therethrough at the longitudinal axis thereof. The turret head 19 adjacent to its upper end and at one side of the rack bar 20 rotatably carries the 20 operating shaft 21 which is also of novel construction. As shown, the shaft 21 includes a spaced bearing portion 22, of a relatively large diameter, and a bearing portion 23 of relatively small diameter, and these bearing 30 portions are received within suitable bearing openings in the turret head or casing. The portion of the shaft between the bearing portions 22 and 23 is provided with right hand threads 24 and the operating pinion 25 is threaded thereon in contact with the shoulder 26 on said shaft defined by the portion 22. A stud 27 is formed axially on the bearing portion 22 and receives the operating crank 27, which crank can be held in place 35 through the medium of a nut 28 threaded on said stud. The end of the shaft opposite the stud 27 also protrudes beyond the turret head or casing and has formed thereon relatively coarse left hand threads 29 for the reception of the jam nut 30 which forms a part 40 of my novel lock for holding the rack bar 20 in its readjusted position. The jam nut is provided with an operating handle or crank 31 and the inner face thereof is provided with 45 a cam surface for binding engagement with one face of the frame or turret head. At this time attention is directed to the fact that the inner and outer faces of the casing or turret head on opposite sides of one bearing opening 50 are provided with annular friction ribs

32 and that the jam nut has its inner face concaved as at 33 for frictional contact with the said annular rib adjacent thereto. Likewise one face of the pinion is also dished or concaved as at 34 for engaging the adjacent annular friction rib 32 when the jam nut is tightened up on said shaft. By this construction it can be seen that when the jam nut is tightened that the shaft will be drawn laterally bringing the jam nut toward the 55 turret head or casing and the pinion in intimate contact with its adjacent friction rib 32, and that the pinion and the jam nut will frictionally contact with said friction ribs 32 and thereby prevent movement of the shaft 80 and consequently locking the rack bar in an adjusted position. It can be seen by this form of lock that the rack bar can be adjusted very finely and at any point on said head. The jam nut 30 can be held on the 85 shaft against accidental displacement therefrom in any desired way, and I can employ a set screw 35 and a washer 36 for this purpose as shown in Figure 10 of the drawings, or I can reduce the end of the shaft to provide a smooth extension 37 for the reception 90 of a washer 38 which can be held in place by a cross pin 39. This is shown in Figure 11 of the drawings. A cross pin 40 can be carried by the upper end of the rack bar 20 in order 95 to limit the downward sliding movement thereof.

Attention is again invited to my turret head 19 and it is to be noted that the same gradually decreases in size toward its lower end and terminates in an axially disposed cylindrical bearing shank portion 41 which is rotatably mounted within the collar 42 carried by the upper arm 16. This collar can be formed on or secured to the arm in any desired way and in the present instance the collar is provided with a yoke 43, the arms of which receive the upper arm or leg 16 of the frame 15 and is secured thereto by suitable bolts or other suitable fastening elements 44. Directly above the bearing shank portion 41 the turret head is provided with an annular shoulder 45 which bears against the upper face of the collar 42. The portion of the bearing shank portion 41 which protrudes below the collar is provided with external threads for the reception of a holding nut or threaded ring 46 which can be held against accidental displacement by the use of a set screw 47. By this arrangement, it can be seen that the turret head or casing 19 is freely revoluble on the arm and in order to hold the turret head in an adjusted position on the frame a set screw 48 is carried by the collar which can impinge against the wall of an 115 annular guide groove 49 formed in the bearing shank 41. To lessen the weight of the turret head and to facilitate the sliding of the rack bar 20 therethrough I prefer to have the inner face thereof only contacting with 120

the rack bar at opposite diagonal points and the other portions of the turret head can be hollowed out if desired.

The lower end of the rack bar 20 carries a novel head 50, which also forms one of the important features of my invention. This head 50 is of a substantially disc-shape with the lower face thereof preferably concaved as at 51 and this head can be formed on or secured to the rack bar in any desired way. In the present instance I have shown the head 50 provided with upstanding spaced arms 52 between which the lower end of the rack bar 20 is received and suitable fastening elements such as a screw 53 can be employed for securing the yoke to the rack bar. The extreme lower end of the rack bar is slotted as at 54 to provide a casing for the reception of an expansion coil spring 55 which bears against a collar 56, at its lower end, formed on the centering pin 57 and against the rack bar at its upper end. This spring 55 normally functions to project the centering pin 57 beyond the lower concaved face 51 of the head 50 and I lay particular stress on the formation of this head and pin and the use thereof will be clearly set forth.

The lower leg 17 of the frame carries a foot 60, which may include a pair of resilient arms 61 bolted or otherwise secured at their inner ends, as at 62, to said leg 17. The resilient arms 61 adjacent to the outer ends thereof are bowed in opposite directions as at 63 and the lower edges of the bowed portions are provided with inwardly directed arcuate flanges 64. The extreme outer ends of the resilient arms beyond the bowed portions can be flared outwardly at opposite directions as at 65. The axial center of the foot 60 between the bowed portions 63 of the arms is located in direct axial alinement with the centering pin 57 and the entire construction of the tool is such that these parts will be held in proper axial alinement at all times.

In use of my improved tool, when it is desired to remove a valve from an internal combustion engine, the head 50 is placed in engagement with the upper face of the valve and the lower surface of said head conforms to the curvature of the valve, while the pin 57 will seat in the recess formed in the axial center of the valve. The foot is now swung over the lower end of the spring and holding washer therefor, after which the crank is rotated in the desired direction for bringing the head 50 and the foot 60 toward one another. This will compress the spring around the valve stem and lift the same off of the holding pin which can now be conveniently removed. Referring to Figure 2 of the drawings, the use of the tool can be readily seen and a fragment of the engine block is indicated by the reference character E while the valve and valve stem are indicated by the reference numerals 66 and 67. The spring is

shown at 68 and the cross pin carried by the stem 67 for the spring 68 is shown at 69. After the spring has been compressed to the desired tension and lifted from off of the pin 69, the crank 31 of the jam nut is turned so as to bring the nut and the pinion in frictional contact with the friction faces 32 of the turret head, which will lock the rack bar against further movement and thereby permit the operator to use both hands for removing the pin 69 or any other work that is to be done.

By my arrangement of turret head 19, the same can be freely turned on the frame, so that the crank can be disposed out of the way of parts of the engine to permit the free manipulation thereof and the turret head also forms means whereby the crank can be disposed on either side of the frame for right or left hand workmen.

My tool is also adapted for use in spring replacements and can be used as an efficient means for recompressing valve springs. When the tool is used for this purpose the dome 70 is disposed between the resilient arms 61 of the foot 60 in the bowed portions 63 thereof and this dome is of conical shape and includes a shank 71 which engages between said arms 61. The conical face of the dome at opposite diametrical points is provided with slots 72 and the inner walls of these slots are flared as at 73 for a purpose which will be later described. When a spring is to be compressed, a clip holder 74 is employed, so as to hold the spring in its compressed condition. The holder in the present instance includes side resilient strips 75 having their terminals at one end provided with hooks 76 for successively engaging the convolutions of the spring during the compressing thereof. The opposite ends of the arms can be inturned as at 77 and secured to the legs of a U-shaped resilient handle 78. The lower end of the spring is placed over the conical dome 70 while the centering pin 57 is placed in the spring through the clip and this pin 57 functions to hold the spring in place against accidental displacement and the conical head acts to hold and center the spring during the compressing thereof. This effectively eliminates bulging of the spring and the working of the spring off center. After the spring is placed in position, the crank can now be rotated for bringing the dome and the head 51 toward one another, which will bring about the compression of the spring. The hooked terminals of the clip engage in the slots 72 and act against the inclined walls 73 of said slots which help to hold the clip in proper position and the hooks to engage the spring convolutions. After the spring is compressed, the rack can be fed up and the spring and holder removed from the tool. The spring in its compressed condition in the

holder can now be readily placed on a valve stem.

- I can make various modifications but the above is the preferred form. However, in 5 Figure 13 I have shown a modified means for locking the turret head in an adjusted position, and in this instance the cylindrical shank portion of the turret head can carry a winged nut 80 for impinging against the 10 lower face of the collar 42, the upper face of which and the lower face of the head can be provided with mating teeth or serrations 81. By this construction, by loosening and tightening the nut 80, the head can be turned and 15 then held in its adjusted position. I can also provide means for adjusting the resilient arms 61 of the foot 60 toward and away from one another and in Figures 14 and 15 I have illustrated one means of adjusting said arms. 20 This means consists of an adjusting bolt 85 which is extended through the arms and the bolt has threaded thereon a winged nut 86. Upon manipulation of the nut 86 on the bolt 25 the arms can be moved or adjusted. In order to prevent turning movement of the bolt during adjusting of the winged nut, the head of the bolt can be provided with lugs 87 which can be received in slots 88 formed in one arm. 30 Other changes may be made without departing from the spirit or the scope of the appended claims, but:

What I claim as new is:

1. A spring compressor and replacer comprising a frame, a foot carried by the lower end of the frame, a head rotatably carried by the upper end of the frame and in axial alignment with said foot, a rack bar slidably carried by said head, a pinion rotatably carried 40 by the head for actuating the rack bar, and means for holding the head in an adjusted position on the frame against accidental turning movement.

2. A spring compressor and replacer comprising a frame, a foot on the lower end of the frame, a rack bar slidably toward and away from the foot and in axial alignment therewith, a head slidably receiving said rack bar and rotatably supported by the upper end 50 of the frame, operating means for the rack bar carried by the head, and means for locking the head in an adjusted position on the frame against accidental turning movement.

3. A valve spring compressor and replacer comprising a frame, a foot carried by the lower end of the frame, a collar carried by the upper end of the frame, a turret head having a longitudinal passage therethrough, a rack bar slidably mounted in said passage in axial alignment with said foot, a shank portion on the lower end of the head rotatably mounted in said collar, said extension defining a shoulder engaging the upper edge of the collar, a nut on said shank portion for engaging the lower edge of the collar, and op-

erating means for the rack bar carried by said head.

4. A valve spring compressor and replacer comprising a frame, a foot carried by the lower end of the frame, a turret head rotatably carried by the upper end of the frame in axial alignment with said foot, means for locking the turret head in an adjusted position against turning movement, a rack bar slidably mounted in said head in axial alignment with said foot, means for raising and lowering the rack bar, and means for locking the rack bar in an adjusted position. 70

5. A valve spring compressor and replacer comprising a frame including substantially parallel upper and lower legs, a foot carried by the lower leg, a collar carried by the upper leg in axial alignment with said foot, a turret head having a reduced cylindrical shank rotatably mounted in the collar, a nut ring threaded on the lower end of the shank for engaging the collar, the shank having an annular groove therein, a set screw carried by the collar for impinging against the walls of said groove, a rack bar slidably supported by the head arranged in axial alignment with the foot, and a pinion carried by the head for operating said rack bar. 75

6. In a valve tool compressor and replacer, a head having a passage therethrough, and bearing openings at one side of said passage, a rack bar slidably mounted in said passage, a transverse shaft having bearing portions rotatably mounted in said bearing openings, a crank for actuating the shaft, a pinion confined on said shaft between said bearing portions meshing with the rack bar, and a lock for said shaft for holding the rack bar in an adjusted position including a jam nut threaded on said shaft for engaging the head and for bringing the pinion into frictional locking engagement with said head. 90

7. A spring compressor and replacer comprising a frame, a foot carried by the lower end of the frame, a head carried by the upper end of the frame in direct axial alignment with said foot, the head having a passageway therethrough and bearing openings at one side of said passageway, a transverse shaft having bearing portions formed thereon rotatably mounted in said bearing openings a 110 crank for operating the shaft a pinion secured to said shaft between said bearing portions, the head having the inner and outer faces thereof at one bearing opening being provided with friction ribs, the inner face of the pinion being concaved for engagement for one rib, a jam nut threaded on said shaft having an inner concave face for engaging the friction rib, on the other face of said head, 115 and means for turning the jam nut on the shaft in intimate engagement with said head, as and for the purpose specified. 120

8. In a spring compressor and replacer, a head having a longitudinal passage there- 130

- through and bearing openings on one side of the passage, a rack bar slidable in said passage, a shaft having bearing portions of different diameters rotatably received in said bearing openings, one of said bearing portions defining an annular shoulder, the shaft being provided with right hand threads between said bearing portions, a pinion threaded on said shaft in engagement with the shoulder having the face thereof opposite to the shoulder concaved, the shaft being provided with an extension beyond one of said bearing portions, a crank connected with the shaft for rotating the same, said threads being opposite to the first mentioned threads on said shaft, the inner and outer faces of the head around one of said bearing openings being provided with friction ribs, a jam nut threaded on said shaft having its inner face concaved, and means for turning the jam nut in intimate contact with the head for moving the concave faces of the pinion and nut into engagement with said friction ribs, as and for the purpose specified.
- 25 9. In a spring replacer and compressor, a sliding adjusting member, a work engaging head carried by the lower end of said member of substantially disc-shape, and a spring pressed centering pin carried by the axial center of said working head.
- 30 10. In a spring compressor and replacer, a sliding adjusting member, a head of substantially disc-shape carried by the lower end of said sliding adjusting member having a concave lower face, and a spring pressed axially disposed centering pin carried by said work engaging head.
- 35 11. In a spring compressor and replacer, a frame, a foot carried by the lower end of said frame, a head carried by the upper end of said frame, a sliding member associated with said head, means for raising and lowering said sliding member, a work engaging head carried by the lower end of said sliding member, and an axially disposed spring pressed centering pin slidable through said head.
- 40 12. In a spring replacer and compressor, a head, a sliding adjusting member, an operating means for said member directly engaging the same, and a lock for holding the adjusting member in adjusted position engaging the head and urging the operating means into frictional contact with the head.
- 45 In testimony whereof I affix my signature.
- 50 JOSEPH E. WAINWRIGHT.
